CLAIM

The ornamental design for a light control panel unit, as
shown and described.

DESCRIPTION

FIG. 1 is a front view of a light control panel unit showing
our new design where the light control panel unit is pale gray
and transparent;

FIG. 2 is a front view showing the state of the light control
panel unit being changed to dark gray and translucent;

FIG. 3 is a front view showing the state of the light control
panel unit being changed to black and opaque;

FIG. 4 is a rear view thereof;

FIG. 5 is a rear view showing the state of the light control
panel unit being changed to black and opaque;

FIG. 6 is a top plan view thereof;

FIG. 7 is a bottom plan view thereof;

FIG. 8 is a right side view thereof;

FIG. 9 is a left side view thereof;

FIG. 10 is an enlarged cross-sectional view taken along line
10-10 in FIG. 1;

FIG. 11 is an enlarged view of a portion of FIG. 8 defined
by demarcated window 11; and,

FIG. 12 is an enlarged view of a portion of FIG. 9 defined
by demarcated window 12.

The broken lines illustrate portions of the light control panel
unit that form no part of the claimed design. The dash-dotted
lines denote the boundary of the claim and form no part of
the claimed design. The oblique line shading shown in the
drawings indicates a transparent or translucent surface.

1 Claim, 10 Drawing Sheets
